SIEGFRIED JUNGHANS, OF BADEN, GERMANY

CASTING UNDER PRESSURE

Application filed July 24, 1928, Serial No. 295,056, and in Germany December 20, 1927.

My invention relates to a new method of casting under pressure and an improved mold for the production of solid or hollow bodies of various forms by casting under pressure.

In the art of casting under pressure as hitherto practised, particularly in cases where the melting point of the metal or alloy to be used lies above 700° C., the molds wear away very soon so that only a relatively small number of castings can be produced successively in one and the same mold. This serious disadvantage is mainly due to the fact that the hot molten metal or alloy is to be thrown or squirted at a high pressure from the inlet opening or nozzle towards the inner surfaces of the mold and consequently the said inner surfaces of the molds are mechanically affected to a high degree the more so as the said surfaces are subjected to an intense cooling action immediately upon the casting operation. Obviously the surfaces cannot withstand for a permanency or a greater length of time such heavy attacks both of the mechanical pressure and of the considerable differences of temperature so that fine fissures and cracks will soon form in the surfaces and such cracks will increase and grow larger at each subsequent casting operation whereby the casting ultimately will be given a bad appearance or will be unserviceable in some cases or require at least an expensive subsequent or finishing treatment.

It will be seen that in many cases the expense incurred to overcome the explained disadvantage considerably offsets the advantage of the method of casting under pressure and renders the latter uneconomical.

The chief object of my invention is to remedy this defect and to overcome the stated disadvantage in a simple and economical manner. With this purpose in view I overcome the excessive strain to which the inner surfaces of the mold are subjected in the previous art due to the enormous heat and the high pressure of the molten metal, by preventing the latter from striking upon the inner surfaces of the mold immediately, that is by diverting the same from its rectilinear path or direction and distributing the jet of

molten metal over a larger area in a most possibly uniform manner so that the molten metal will be introduced into the mold at a reduced pressure and at a lower temperature.

Obviously the method can be carried out in practice in quite a variety of different ways. Thus the diversion or deviation and the distribution of the jet of molten metal may be brought about in various different ways by inserting a suitable obstruction or even, if desired, by simply causing the molten metal to take a tortuous path in the mold. At any rate, it is essential that the current or jet of molten metal will be diverted in a manner that no metal coming direct from the melting oven, will strike immediately the inner surfaces of the mold. In other words, the jet of molten metal rushing at a considerable pressure into the mold is influenced in a manner that the molten metal will enter the space or chamber of the mold, properly speaking, at a reduced uniform pressure and at a rather decreased uniform temperature. It goes without saying that my improved method is applicable both in connection with molds having a single molding space or chamber only and in connection with molds having a plurality of spaces or chambers.

With the above recited object in view, reference is had to the following specification and drawings in which there is exhibited one example or embodiment of a mold designed for carrying out the invention but which is in no way intended as a limitation upon the scope of the appended claims as it is to be clearly understood that variations and modifications which fairly fall within the scope of said claims, may be resorted to when found expedient.

In the accompanying drawings forming a part of this specification and showing, for purposes of exemplification, a mold having a plurality of molding chambers:

Figure 1 illustrates the construction thereof without any cooling or preheating means, and

Figure 2 illustrates a modification equipped with cooling or preheating means.

In both cases shown the jet of molten metal is diverted by a distributing member v^1 and

v^2 , respectively, provided in the path the jet of molten metal is caused to take, and located across or transversely to the inner charging orifice. The jet of molten metal impinges, 5 on its way through the orifice b into the mold f^1 or f^2 , respectively upon the distributing member so as to be diverted and directed thereby towards and into the lateral molding chambers 1, 2 etc. At the same time the pressure 10 of the molten metal while thus being uniformly spread, will be reduced due to the impact on the distributing member and the distribution accomplished thereby. The fact that those surfaces of the distributing member which are directly struck by the jet of molten metal, are damaged by cracking, is 15 of no account as regards the castings to be produced, since the portion of the casting formed in the vicinity of the distributing surfaces forms part of the dead head which in any case is but waste to be returned to the melting furnace.

Moreover the distributing member may be constructed and arranged so as to be capable 20 of being readily exchanged when injured and worn, for a new one, so that the mold will be adaptable for use for a comparatively great length of time, preferably by providing suitable channels in the wall of the mold, 25 as shown in Figure 2, the distributing member may be improved so as to be capable of being cooled or subjected to a preliminary heating.

From the foregoing, it is believed, that the 30 advantages and novel features of my invention will be readily understood and, therefore, further detail description is deemed unnecessary. I do not of course desire to be limited to any particular way of carrying 35 out the improved method or to the exact details of construction and arrangement shown and described as modifications are no doubt possible as hereinbefore already intimated, which would still come within the 40 scope of the invention and I aim in the appended claims to embrace all modifications falling fairly within the scope of my invention.

What I claim is:—

50 1. A multi-part pressure casting mold, comprising a pair of mold sections, one section having a charging channel therein and branch channels in the sections terminating at one end into a mold chamber and the 55 other end into the charging channel at right angles thereof; and a distributing member in the other mold section opposite the charging channel and having a depression adjacent thereto in each charging channel forming 60 shock and connecting surfaces for the purpose of reducing the speed, pressure and temperature of the jet of molten metal to prevent injury to the mold chamber.

65 2. A multi-part pressure casting mold, comprising a pair of mold sections, one sec-

tion having a charging channel therein and branch channels in the sections terminating at one end into a mold chamber and the other end into the charging channel at right angles thereof; a distributing member in the other mold section opposite the charging channel and having a depression adjacent thereto in each charging channel forming shock and connecting surfaces for the purpose of reducing the speed, pressure and temperature of the jet of molten metal to prevent injury to the mold chamber; and means for cooling and heating said shock and connecting surfaces of the distributing member.

70 3. A multi-part pressure casting mold, comprising a pair of mold sections, one section having a charging channel therein and branch channels in the sections terminating at one end into a mold chamber and the other end into the charging channel at right angles thereof; a distributing member in the other mold section opposite the charging channel and having a depression adjacent thereto in each charging channel forming shock and connecting surfaces for the purpose of reducing the speed, pressure and temperature of the jet of molten metal to prevent injury to the mold chamber; hollow chambers adjacent said shock and connecting surfaces and concentric with said distributing member and said charging channel; and channels in the wall of the mold terminating in said hollow chambers for heating and cooling said hollow chambers and said shock and connecting surfaces.

75 80 85 90 95 100 105 110 115 120 125 130

In testimony whereof, I affix my signature.

SIEGFRIED JUNGHANS.
